UNITED STATES PATENT OFFICE.

IRVIN F. DITTMAR, OF WILLIAMSPORT, PENNSYLVANIA, ASSIGNOR TO THE CROOKS-DITTMAR COMPANY, OF WILLIAMSPORT, PENNSYLVANIA, A CORPORATION OF PENNSYLVANIA.

YIELDABLE GUIDE FOR COATING MACHINES.

Application filed July 27, 1922. Serial No. 577,869.

To all whom it may concern:

Be it known that I, IRVIN F. DITTMAR, a citizen of the United States, residing at Williamsport, in the county of Lycoming and State of Pennsylvania, have invented certain new and useful Improvements in Yieldable Guides for Coating Machines, of which the following is a specification, reference being had therein to the accompanying drawing.

This invention relates to certain new and useful improvements in yieldable guides for coating machines and more particularly to guides adapted to be used in connection with machines for coating strips of lumber in which the strip is passed through the machine on edge, the object being to provide a guide which is so constructed that it will yield so as to allow crooked pieces and pieces showing a variation in thickness to pass through without stoppage, which causes roller marks to spoil the pieces at the point of roller contact, thereby overcoming the difficulties now existing in having to stop the machine and remove the strip when it has become jammed in the guideway.

Another and further object of the invention is to provide a yieldable guide formed of superposed guiding members, each guide member being formed of spaced members held in proper relation with each other in such a manner that they are capable of moving laterally in order to allow an irregular strip to pass freely through the guide.

Other and further objects and advantages of the invention will be hereinafter set forth and the novel features thereof defined by the appended claims.

In the drawings,

Figure 1 is a perspective view of a portion of a guideway constructed in accordance with my invention;

Figure 2 is a vertical section through the same showing the manner of connecting the guide members of the guideway to the supporting members;

Figure 3 is a vertical section through a slightly modified form of guideway;

Figure 4 is a vertical section through still another form of guideway;

Figure 5 is a vertical section through still another form of guideway; and

Figure 6 is a vertical section through another form of guideway.

In the drawing 1 and 2 indicate supporting members which are herein shown in the form of angle irons to which are adapted to be connected guide members 3 and 4 having notches 5 and 6 at the point of application of the coating so as to allow the strip to be coated as it passes through the guideway.

The upper guide 3 is formed of an inverted U-shaped strip of flexible material having its lower edges cut away to form a female guiding edge and the lower guide member 4 is formed of a U shaped strip of flexible metal having its upper edges cut away to form a male guiding edge.

The guide members formed with this particular construction of guiding edges are especially adapted to receive strips of lumber having interlocking male and female edges and it is, of course, understood that the particular construction of the guiding edges can be changed to fit the shape of the edges of the strip to be coated and therefore I do not wish to limit myself to the use of a guideway formed of guide members having any particular construction of guiding edges as I am aware that the configuration of the guiding edges can be readily changed to conform to the edge of the strip of lumber to be coated without departing from the spirit of my invention.

In the drawing I have shown the guide member 3 connected to the support 1 by a bolt 9 and spaced therefrom by spring washer 10 in order to allow the legs of the guideway to expand and contract. The lower guide 4 is connected to the lower support by a bolt 11 which passes through one of the legs and is provided with spring washers 12 and 13 in order to allow the legs of the guideway to expand and contract, it, of course, being understood that a number of bolts are employed for connecting the guide members to the supports and while I have shown means for connecting these guide members so as to allow the inner leg of each guide member to expand and contract, I am aware that by rigidly connecting the guide members to the support, the outer legs of the substantially U-shaped guide members will expand and contract so as to allow a strip of lumber to pass freely through the guideway formed by said members and I do not wish to limit myself to any particular means for connecting the

guide members forming the guideway to the supports, as I am aware that these members can be connected to the supports in various ways without affecting the operation of the members.

In the preferred embodiment of the invention as shown in Figures 1 and 2, the guideway formed by the guide members 3 and 4 is formed of substantially U-shaped members to form yieldable legs, while in Figure 3 the upper and lower guide members forming the guideway are formed of spaced strips of metal 14 and 15, the upper strips 14 being spaced apart by tapering block 16 and secured together by a bolt 17 on which is mounted a spring washer 18 which allows the spaced strips to move in respect to each other.

The spaced strips forming the guide member 15 are spaced apart by a tapering block 19 and are secured together by a bolt 20 which passes through the block and is provided with a spring washer 21, the upper edge of the strip being cut away to form a male guiding edge.

In this construction, the spaced strips forming the guide members are yieldably held together so as to provide a yieldable guideway for the strip as it passes therethrough, as clearly shown.

In Figure 4 I show the upper guide member 22 formed of spaced strips secured together by bolts 23 and 24 provided with spring washers 26 and spaced apart at their upper end by a block 27 which allows the spaced members constituting the guide member to move in respect to one another, the lower edges being cut away to form a female guiding edge. The lower guide member 28 formed of spaced strips secured together by bolts 29 and 30 carries spring washers 31 arranged between the strips in such a manner that the strips are free to move in respect to one another, the lower nut of the bolt 30 being drawn tight while the upper nut of the bolt 29 is spaced from the strip so as to allow the strips to yield in respect to one another, the upper edges of the strips being cut away to form a male guiding edge.

In Figure 5 of the drawing I show a guideway formed of upper and lower guide members 32 and 33, the upper guide member 32 being formed of a pair of strips between which is arranged an elastic spacing member 34, said strips being secured together and held so as to hold the elastic strip under compression by bolts 35 which are provided with spring washers 36.

The lower guide 33 is formed of a pair of strips between which is arranged an elastic spacing member 37, said strips being secured together by bolts 38 and 39, the nut on the bolt 38 being drawn tight so as to compress the elastic material between the

strips while the nut on the bolt 39 is loose in order to allow the strips to move in respect to one another.

In Figure 6 I show a guideway formed of an upper guide member 40 and a lower guide member 41, the upper guide member being formed of a pair of strips spaced apart by elastic washer 42 and secured together by bolts 43 carrying spring washers 44. The lower guide member 41 is formed of strips spaced apart by elastic washers 45 and secured together by bolts 46 and 47, the nut of the bolt 46 being drawn tight so as to place the elastic material under compression while the nut on the bolt 47 is loose in order to allow the strips to move in respect to one another so that the strip will pass freely through the guideway formed by the guide members.

While in the drawing I have shown various forms of mounting and constructing the guide members forming the guideway, I am aware that various changes can be made without departing from the spirit of my invention and I do not wish to confine myself to the use of any particular construction of spring washer as I am aware that a washer having more than one convolution can be used or a flat spring could be substituted for the washer and the same result obtained.

From the foregoing description it will be seen that I have provided a guideway formed of a pair of spaced guiding members, each guide member having spaced guiding edges which are yieldably held in a predetermined position so as to allow the guiding edges to expand and contract to conform to the shape of the strip in its passage therethrough to prevent the strip from jamming so that the speed of the machine for coating the strip can be increased and all danger of having the strip jammed eliminated.

The ingoing edge of the guides forming the guideway are preferably positioned so as to allow the strip to pass freely into the guide at the feed end thereof, this being accomplished by drawing the strips of the lower guide together and releasing the tension on the strips of the upper guide to allow them to separate, which provides a feed end for the guideway and is of such a construction that the strip can be readily placed between the guideway and fed easily therethrough.

In Figure 1 of the drawing I have shown the guide strips 3 and 4 forming the guideway with notches 5 and 6 and while I have only shown a portion of the guideway with a pair of opposing notches, it is, of course, understood that the guideway can be formed with any number of notches desired to meet the specific requirement of the coating being applied. I am also aware that the particular shape of these notches can be changed

to conform to the shape of the applying device.

What I claim is:—

1. A guideway for coating machines comprising spaced guide members, each guide member having yieldably spaced guiding edges.

2. A guideway for coating machines comprising spaced guides, each guide being formed of yieldably spaced members and means for yieldably supporting said guide.

3. A guideway for coating machines comprising spaced substantially U-shaped guides, one guide being provided with a male guiding edge and the other guide with a female guiding edge.

4. A guideway for finishing machines comprising spaced notched guides, each guide being formed of spaced members yieldably held in respect to one another and means for yieldably supporting said guide.

5. A guideway for wood finishing machines comprising spaced guiding members,

each guiding member being formed of spaced members, bolts for securing said members together and flexible means disposed on said bolts for allowing said members to move in respect to one another.

6. A guideway for wood coating machines comprising spaced guides, each guide being formed of spaced members having beveled edges, bolts for securing said members together and flexible means disposed between said members and on said bolts for yieldably holding said members in spaced relation.

7. A guideway for wood finishing machines comprising spaced guide members provided with notches, said guides being formed of spaced members, bolts for securing said guides together, yielding means disposed between said members and flexible members disposed on said bolts.

In testimony whereof I hereunto affix my signature.

IRVIN F. DITTMAR.
